CASING FOR A THERMOSTAT

Rooney W. Davis, Webster Groves, Mo., assignor to
Missouri Automatic Control Corporation, St. Louis,
Mo., a corporation of Missouri

Application November 15, 1954, Serial No. 33,086

Term of patent 14 years

(Cl. D52—7)

FIG 2

FIG 3

FIG 1

FIG 4

Fig. 1 is a side elevation of a casing for a thermostat showing my new design;

Fig. 2 is a plan view thereof;

Fig. 3 is a front elevation thereof; and

Fig. 4 is a bottom view thereof.

I claim:

The ornamental design for a casing for a thermostat, substantially as shown.
